UNITED STATES PATENT OFFICE

2,647,784

DIE SET HANDLING FLANGE AND COACTING
HOOKKasimir Janiszewski, Milwaukee, Wis., assignor to
Superior Steel Products Corp., Milwaukee, Wis.,
a corporation of Wisconsin

Application September 2, 1948, Serial No. 47,353

14 Claims. (Cl. 294—1)

1

This invention relates to improvements in die set handling flanges and co-acting hooks.

It is a primary object of the invention to provide one or both plates of a die set with novel flange means which not only enable a hold down clamp to operate effectively on the die shoe but also facilitates both manual handling and the application of either conventional or novel hoisting means for positioning the die set or moving it respecting the bed of a press in which such set is used.

More specifically stated it is a purpose of the invention to provide one or both plates of a die set with laterally projecting horizontal flanges, each plate preferably being provided with cooperating vertical surfaces for protecting the operators' fingers and for positioning a hoist and a hold down clamp. From the standpoint of one species of my invention it is a purpose to provide more than one horizontal flange. From the standpoint of another species of my invention it is my purpose to provide a convoluted marginal flange and a special co-acting clip which may be connected with a hoist and is formed for engagement and disengagement with such flange to facilitate manipulation of the die set.

It is a further object of the invention to provide a novel clip for the purposes aforesaid. Other objects will be apparent from the following detailed disclosure of my invention.

In the drawings:

Figure 1 is a plan view of a die set embodying my invention as it appears when the shoe is anchored to the bed of a press through hold-down means engaged with the novel laterally projecting flange with which the shoe of my improved die set is equipped.

Figure 2 is a fragmentary detailed view in perspective showing one side of a shoe equipped with a flange embodying my invention and engaged by a hold-down.

Figure 3 is a view in perspective showing a slightly different shape of shoe provided with a flange embodying my invention, the shoe being partially supported by a hoist connected with such flange.

Figure 4 is a view in perspective showing an assembled punch holder and die shoe both equipped with a modified type of flange having a corrugated margin in accordance with another phase of my invention.

Figure 5 is a fragmentary detailed view in perspective showing a modified way of making a corrugated lateral flange.

Figure 6 is a view in front elevation of the die set shown in Fig. 4 illustrating the manner in

2

which my novel supporting clip is engageable with the novel flange shown in Fig. 4 for lifting the shoe.

Figure 7 is a fragmentary detailed view in end elevation of the parts shown in Fig. 6.

Figure 8 is a detailed view in perspective showing a heavier die shoe equipped with three flanges and arranged to be lifted by a novel hoist having three chains and three clips engageable with the respective flanges.

Figure 9 is a detailed view in perspective showing on an enlarged scale the novel clip used in conjunction with the convoluted or corrugated flange of the type illustrated in Figures 4 to 8.

Figure 10 is a diagrammatic view in side elevation showing how a corrugated or convoluted flange of the type shown in Fig. 4 can readily be manufactured.

Figure 11 is a view in perspective fragmentarily illustrating another way in which the detachable clip can be releasably anchored to the manipulating flange of the plate.

Referring first to the construction shown in Fig. 1 and Fig. 2, I have illustrated at 15 a die shoe provided with the usual leader pins at 16 for guiding the punch holder. Each of the leader pins is conventionally mounted in a projecting ear portion 17 of the shoe. In accordance with the present invention, a handling flange is welded at 18 to the side of the shoe and preferably also welded to the ear at 17, the location of the flange being preferably about midway of the thickness or height of the shoe.

Integrally welded to the shoe and to the flange 18 is a channelled or U-shaped member 19 which provides vertical flanges at 20 and 21 and a horizontal flange at 22. The hold-down finger 23 extends into the U-shaped member 19 and is engaged with the bottom flange 22 thereof under compression of the clamp screw 24 which connects the hold-down to the bed of the press. The finger 23 may be, and desirably is, supported at its outer end by a heavy shim 25 which leaves the finger approximately horizontal. The vertical flanges 20 and 21 respectively welded to the under surface of the horizontal flange 18 serve to confine the hold-down finger against lateral displacement, thereby making it perfectly secure when in use.

I preferably provide a further vertical flange at 26 welded to the shoe and to the under surface of flange 18 and spaced from the flange 20 at approximately the same spacing as flange 21 so that the three flanges are approximately uniformly spaced at the side of the shoe. This arrangement facilitates the application of a special

50
55

hoisting clip such as that shown in Fig. 9 and later to be described. However, the horizontal flange 18 is also desirably provided opposite its center of gravity with an aperture at 28 into which a conventional hoisting hook such as that shown at 29 in Fig. 3 is readily engaged for lifting the shoe for its manipulation to and from the press. The structure described and shown on the right hand side of the shoe in Fig. 2 is desirably duplicated at the left hand side of the shoe as indicated in Fig. 1.

In Fig. 3 the shoe differs in shape, being long and narrow. The leader pins 16 may be identical with those above described but are located at the remote ends of the elongated shoe 150. The laterally projecting flanges 180 are similar to the flange 18 already described but are longer, desirably extending substantially the entire length of the shoe 150. Since they are longer they are provided with a number of the U-shaped members 19 instead of with a single one thereof as in the device shown in Figures 1 and 2. Obviously the hold-down fingers 23 may be applied in any one or more of the channel shaped members 19. Any desired number of apertures may be provided in the flanges 180 to receive the hoist hook or hooks 29.

For hoisting purposes the work of fabricating the hoisting flanges may be materially reduced by adopting one or another of the constructions shown on sheet 2 of the drawings. In the construction shown in Fig. 4, each of the flanges 181 applied to the shoe 151 and the punch holder 33 has one planiform surface 182 and one convoluted surface 183. A pair of the special flanges shown in Fig. 4 may readily be made with economy of material in the manner indicated in Fig. 10 by using a torch to make a convoluted cut at 31 through a piece of bar stock to form the two members 184, the outer faces of the bar stock forming the planiform surfaces 182 and the path of the torch forming the convoluted surfaces 183. Two flange devices may thus be made from a bar only one fourth inch thicker than would be required for one. The resultant effect is to produce in one piece a flange comparable to the flange 18 of Fig. 1 from which there are depending flanges in the form of uniformly spaced teeth. The product is welded to the side of the plate 151 or 30 in the same manner as the fabricated assembly is welded to the side of the plate 15 in Fig. 1 and Fig. 2.

A somewhat similar device may be made as suggested in Fig. 5 by simply convoluting a piece of strap iron in the manner indicated at 184 and welding it to the side of the plate 153.

With my improved type of flange I preferably employ an improved hoisting clip which may have the construction shown in Fig. 9 or that shown in Fig. 11, or that shown in Fig. 6 and Fig. 7. In either case the clip comprises a plate portion 32 or 320 which comprises the top of an open channel, the bottom of the channel comprising a pair of spaced fingers at 33. Across the back web portion 34 of the channel is welded integrally a ring at 35. I may provide the top flange 32 and the respective fingers 33 with registering apertures 36, 37 (Figs. 6 and 7), in which case I may also provide similarly spaced apertures at 38 (Fig. 4) in the lateral flange provided on the shoe and on the punch holder respectively. The apertures in question are not essential but where used they accommodate locking pins 40 which pass downwardly through the clip and through the flange on the die plate, thereby releasably locking the

clip to the die plate and making it possible to connect the hoisting hook 290 to the ring 35 without any possibility of the clip becoming disengaged from the plate. The connection is particularly useful when a hoist is connected with one clip only, as in turning a die plate over. In ordinary vertical lifting, the use of the locking pins 40 is not at all essential as the tension of the hoist chains is exerted in a direction to hold the clip to the flange. However, for special manipulative purposes as last described, it may be desirable to lock the clip to the plate by means of a pin 40 or otherwise so that it cannot become disengaged if the tension is outwardly rather than inwardly.

Another way in which this can be accomplished is shown in Figure 11. The clip may be identical with either of those already described. As shown, it is the same as that shown in Fig. 9 with the exception that it has a channel 321 cut in its under surface. For cooperation therewith the flange 188 provided on the die set plate has a complementary channel at 189, each of the channels 321 and 189 being semi-cylindrical and adapted to receive the key 400 which is detachably slid therein to anchor the clip to the flange. For manipulation of the key, it may be provided with an upstanding handle at 401. A device so constructed is sufficiently strong so that it will handle a 5000 pound plate with ease and yet the clip may be instantly applied or released by simply inserting or withdrawing the key 400.

Instead of having the ring 35 integral with the clip as shown in Fig. 9, I may provide the clip with ears 41, 42 spanned by a pintle at 43 pivotally supporting the ring 350 so that the ring is self-adjusting in position when engaged by the hook in the manner indicated in Figures 6 and 7.

While all of the various die shoes and punch holders thus far described have had the respective handling flanges located midway of their sides, Fig. 8 shows how the heavy shoe 151 may have the handling flanges 185 and 186 located adjacent its forward outer corners and the handling flange 187 located midway of its back. Using three of the clips as shown in Fig. 9, each connected with one of the chains 45, 46 and 47 of a suitable hoist, it is readily possible to manipulate even the heaviest plate. What is more, the locations of the several clip flanges in the specific locations indicated, facilitate manipulation of a heavy shoe to turn it upside down or from side to side or to any desired position. It will be apparent that if the hook 41 is disengaged from the flange 187 at the rear of the shoe, for example, all of the lifting force of the hoist will be applied to the front corners of the shoe and it will readily be possible to turn the shoe up for manipulation or, if desired, to turn it over.

In no case can the clip slip longitudinally of one of the flanges with which it is engaged, since the downwardly projecting teeth or vertical flange portions of the convoluted lower surface are engaged by the fingers 33 to prevent any such displacement. While the clip as shown is particularly devised for engaging the convoluted flanges shown in Figures 4 to 10, it will be apparent that the identical clip, with or without modification as to form, may also be used to provide a secure grip on the type of flange shown in Fig. 2, or that shown in Fig. 3.

When a complete die set, such as that of Fig. 4, is to be handled as a unit, as in Fig. 6 and Fig. 7,

the flange 181 applied to the punch carrier plate 30 is desirably inverted, with its convolutions or teeth uppermost. Then when the hoist hook 290 is engaged with a clip attached to the shoe 151, the chain 44 attached to the hook will enter between the convolutions 183 of the flange on the punch carrier and the interlock thus effected will hold the entire set upright. (Figs. 6 and 7.)

Assuming that the plates of the die set are not too heavy to be lifted manually, it will also be apparent that the channels between the downwardly projecting teeth, or the pockets provided by the vertical flanges of the device of Figures 2 and 3 are admirably adapted to receive the operator's fingers and to secure the operator's hands against slipping respecting the plate, and also to protect the fingers from possible damage through contact with the underlying bed of a press. Thus, whether the die set is manipulated by hand or by power, it can be handled more securely and more positively and more easily through the use of the means embodying this invention, the flange being in every instance located intermediate the top and bottom of the plate to which it is marginally applied and the vertical flanges or fingers preferably extending vertically from the horizontal portion of the flange and providing recesses for the fingers.

I claim:

1. In a device of the character described, the combination with a die plate having laterally projecting flange means with horizontal and mutually spaced vertical portions, of a clip comprising a channel engageable with said flange means and having spaced fingers for separately engaging between said vertical portions, whereby to fix said clip against displacement respecting said flange.

2. In a device of the character described, a clip comprising a channel having a flange portion, a back web portion, and a plurality of spaced fingers opposing said flange portion and spaced therefrom, together with ring means connected with said clip and to which a hoist may be connected.

3. The device of claim 2, in which the clip is provided with registering apertures in the flange and the fingers respectively, together with pins adapted to pass through said apertures for connecting said clip with an object to be lifted.

4. The combination with a die plate provided with a flange having a longitudinally extending channel, of a clip having a hoist coupling and slotted to receive said flange, the clip having a channel complementary to that of the flange, together with a key adapted to be slidably inserted in the registering channels of the clip and flange to secure the clip against separation from the plate.

5. The combination set forth in claim 4 in which the clip and the flange have interlocking teeth disposed at an angle to the respective channels aforesaid whereby to preclude displacement of the clip longitudinally of the flange.

6. In a die set the combination with a die plate, of a flange projecting laterally therefrom and extending longitudinally along one side of the plate, said flange having convoluted teeth on its lower surface and a longitudinally extending channel on its upper surface, together with a clip having a top plate adapted to engage the upper surface of the flange and having a complementary registering channel, said clip including a pair of spaced fingers adapted to enter convolutions in the lower surface of the flange, to lock the clip against displacement longitudinally

of the flange, together with a key in the registering channels of the clip and the flange detachably securing the clip against outward displacement from the flange, the clip having hoist attaching means.

7. In a device of the character described, the subcombination which comprises a clip having an upper plate, a pair of fingers projecting in mutually spaced relation to each other and to the plate, a hoist attaching means and means for locking the clip to a member intervening between said plate and fingers.

8. In a die set including a die carrying plate so heavy and unwieldy as to endanger an operator's fingers whether the plate is lifted manually or with a hoist having a fingered plate lifter, the combination with such a plate having upper and lower faces and a thick edge, of flange means having a generally horizontal extent and attached to said plate and projecting laterally from said edge intermediate the upper and lower faces, and a series of generally upright flanges dimensioned to fit between an operator's fingers and disposed opposite the central portion of the plate and extending with substantial vertical height substantially to the edge of said first-mentioned flange means between the first mentioned flange means and the level of the bottom face of the plate, said upright flanges and the flange means first mentioned forming recesses dimensioned to receive alternatively the operator's fingers and the corresponding fingers of a hoist at a point at which the plate is substantially in balance and to secure such fingers against slippage along the flange means and to protect such fingers from being caught beneath the plate or the first mentioned flange means in the lowering of the plate.

9. In a die set including a die-carrier plate so heavy and unwieldy as to endanger an operator's fingers whether the plate is lifted manually or with a hoist having a fingered plate lifter, the combination with such a plate having upper and lower faces and a thick edge, of flange means having a generally horizontal extent and attached to said plate and projecting laterally from said edge intermediate the upper and lower faces, and a series of generally upright flanges between the first mentioned flange means and the level of the bottom face of the plate, said upright flanges and the flange means first mentioned forming pockets dimensioned to receive alternatively the operator's fingers and the corresponding fingers of a hoist and to secure such fingers against slippage along the flange means and to protect such fingers from being caught beneath the plate or the first mentioned flange means in the lowering of the plate, said upright flanges being directly connected with the plate edge.

10. In a die set including a die-carrier plate so heavy and unwieldy as to endanger an operator's fingers whether the plate is lifted manually or with a hoist having a fingered plate lifter, the combination with such a plate having upper and lower faces and a thick edge, of flange means having a generally horizontal extent and attached to said plate and projecting laterally from said edge intermediate the upper and lower faces, and a series of generally upright flanges between the first mentioned flange means and the level of the bottom face of the plate, said upright flanges and the flange means first mentioned forming pockets dimensioned to receive alternatively the operator's fingers and the corresponding fingers of a hoist and to secure such fingers against slippage along the flange means and to protect such fingers from being caught beneath the plate or the first mentioned flange means in the lowering of the plate, said upright flanges being directly connected with the plate edge.

fingers against slippage along the flange means and to protect such fingers from being caught beneath the plate or the first mentioned flange means in the lowering of the plate, said upright flanges comprising the legs of mutually spaced U-shaped channel sections, each of which comprises a bottom web, the said legs being welded to the plate edge and to the first flange means, and the said bottom webs closing alternate pockets, the intervening pocket being open downwardly.

11. In a die set including a die-carrier plate so heavy and unwieldy as to endanger an operator's fingers whether the plate is lifted manually or with a hoist having a fingered plate lifter, the combination with such a plate having upper and lower faces and a thick edge, of flange means having a generally horizontal extent and attached to said plate and projecting laterally from said edge intermediate the upper and lower faces, and a series of generally upright flanges between the first mentioned flange means and the level of the bottom face of the plate, said upright flanges and the flange means first mentioned forming pockets dimensioned to receive alternatively the operator's fingers and the corresponding fingers of a hoist and to secure such fingers against slippage along the flange means and to protect such fingers from being caught beneath the plate or the first mentioned flange means in the lowering of the plate, said first flange means having an aperture opening through it into at least one of said pockets for the anchoring of the finger of a lifter in such pocket.

12. In a die set including a die-carrier plate so heavy and unwieldy as to endanger an operator's fingers whether the plate is lifted manually or with a hoist having a fingered plate lifter, the combination with such a plate having upper and lower faces and a thick edge, of flange means having a generally horizontal extent and attached to said plate and projecting laterally from said edge intermediate the upper and lower faces, and a series of generally upright flanges between the first mentioned flange means and the level of the bottom face of the plate, said upright flanges and the flange means first mentioned forming pockets dimensioned to receive alternatively the operator's fingers and the corresponding fingers of a hoist and to secure such fingers against slippage along the flange means and to protect such fingers from being caught beneath the plate or the first mentioned flange means in the lowering of the plate, said flange means and upright flanges together providing a convoluted surface wherein successive convolutions opening toward one of said faces provide the pockets aforesaid.

13. In a die set including a die-carrier plate so heavy and unwieldy as to endanger an operator's fingers whether the plate is lifted manually or with a hoist having a fingered plate lifter, the combination with such a plate having upper and lower faces and a thick edge, of flange means having a generally horizontal extent and attached to said plate and projecting laterally from said edge intermediate the upper and lower faces, and a series of generally upright flanges between the first mentioned flange means and the level of the bottom face of the plate, said upright flanges and the flange means first mentioned forming pockets dimensioned to receive alternatively the operator's fingers and the corresponding fingers of a hoist and to secure such fingers against slippage along the flange means and to protect such fingers from being caught beneath the plate or the first mentioned flange means in the lowering of the plate, said flange means and upright flanges together comprising a curvilinearly convoluted strip in which a pocket opening toward one face of the plate intervenes between pockets opening toward the opposite face of the plate.

14. In a die set including a plate so heavy as to require a fingered hoist connector to be keyed thereto for handling, the combination with such a plate having spaced faces and a thick edge, of a flange connected with the plate and projecting laterally from said edge between the levels of such faces, said flange having at one side pocket-forming means extending toward one of said faces to form at least one finger-receiving pocket and having at its opposite side a key-receiving channel extending longitudinally of the flange in general parallelism with said edge and opening toward the other face of the plate.
